UNITED STATES PATENT OFFICE.

G. W. VAN BRUNT, OF ROLLING PRAIRIE, WISCONSIN.

IMPROVEMENT IN SEEDING-MACHINES.

Specification forming part of Letters Patent No. 33,720, dated November 12, 1861.

To all whom it may concern:

Be it known that I, G. W. VAN BRUNT, of Rolling Prairie, in the county of Dodge and State of Wisconsin, have invented a new and Improved Seed-Sower and Cultivator; and I do hereby declare that the following is a full, clear, and exact description of the same, reference being had to the annexed drawings, making a part of this specification, in which—

Figure 1 is a transverse vertical section of my invention, taken in the line x x , Fig. 2. Fig. 2 is a longitudinal central section of same, taken in the line y y , Fig. 1. Fig. 3 is a detached perspective view of one of the seed-distributing devices.

Similar letters of reference indicate corresponding parts in the several figures.

To enable those skilled in the art to fully understand and construct my invention, I will proceed to describe it.

A represents a rectangular frame, which is mounted on two wheels, B B, and has a box, C, placed on it, extending its whole width.

Within the box C there is placed a shaft, D, on one end of which a pinion, E, is fitted, said pinion gearing into a wheel, F, which is attached concentrically to one of the wheels B.

On the shaft D there is secured a series of hubs, G, which may be described as being cylinders provided with radial flanges a , the spaces b between which form seed-cells. Each hub G has a shell or hollow cylinder, H, fitted on it. These cylinders or shells are slotted longitudinally, as shown at c , to receive the flanges a of the hubs G, the portions of the shells between the slots c fitting snugly in the spaces b between the flanges a of the hubs, as clearly shown in Fig. 3.

The shells or hollow cylinders are each provided with a flange, d , at their outer ends, and these flanges are fitted in sockets I, attached to a slide, J, which forms the bottom of box C. The slide J is moved or actuated by a lever, K, and by this movement of the slide the shells or cylinders H may be shoved a greater or less distance on the hubs G, and the capacity of the seed-cells varied as circumstances may require.

Directly over the box C there is placed a seed box or hopper, L, the bottom of which is provided with a register, M, formed of a stationary perforated plate, f , and an adjustable perforated plate, e . The perforations g of these plates are directly over the hubs G on shaft D.

Within the upper hopper, L, there is placed longitudinally a shaft, N, on which a series of wheels, O, provided with radial arms h , are placed. The wheels O are directly over the perforations g of the register M. In the lower part of the seed-box there are placed inclined plates h' , arranged as shown in Fig. 2, the wheels O being over the centers of the valleys. The shaft N has a pinion, P, at one end of it, which gears into the pinion E of shaft D.

To the under side of slide J there is attached a series of pendent tubes, Q, which are of flaring or bell form, and are directly under the hubs G. In the lower part of each tube Q there is fitted or placed a cone, R. These cones are smaller in diameter than the interior of the tubes Q, and a space is consequently left between the covers and the tubes for the discharge of the seed. The cones are slightly concave, corresponding in a reverse manner with the interior of the tubes Q, and the cones may be secured in the tubes Q by pins a^* .

From the above description the manner in which the seed is distributed will be readily seen. The wheels O discharge the seed from the hopper L through the perforations g of the register M, the seed falling into the seed-cells b , which rotate in contact with plates b^* in the top of box C, the register M resting or bearing on said plates b^* .

The quantity of seed to be sown on a given surface or area of ground may be varied by adjusting the slide J so that the shells or cylinders H may be adjusted a greater or less distance on G, and the seed-cells b varied in capacity as required. The seed drops from the cells b into the tubes Q, and falls on the cones R, and is discharged from the lower ends of the tubes Q in a scattered or broadcast state. The form or shape of the tubes Q, in connection with the cones R, effects such result. The discharge of seed from hopper L may be entirely cut off by adjusting the plate e of the register so that the perforations g will not be in line with each other.

S is a shaft, the ends of which are fitted in bearings c^* at each end of the frame A, and on this shaft S there is placed loosely a series of bars, T, the back ends of which have cultivator or harrow teeth U attached, of any suitable form. The bars T are allowed to swing freely on the shaft S, and on this shaft, and between the bars T, collars V are placed loosely,

said collars keeping the bars T a proper distance apart. The back part of each bar T has a pin, d^* , projecting at right angles from its surface, and these pins d^* pass loosely through a bar, W, and have heads e^* on their upper ends. The bar W is connected by a chain, f^* , to a lever, X, on the back part of frame A. The pins d^* are of sufficient length to admit of each bar T rising and falling to a certain extent independently of the others, and by actuating the lever X the whole number of bars T may be elevated simultaneously above the surface of the ground. The teeth U harrow in the seed and pulverize the soil behind the tubes Q.

Having thus described my invention, what I claim as new, and desire to secure by Letters Patent, is—

The arrangement of the rotating hubs G and sliding shells or cylinders H, the latter being connected with the slide J, having the tubes Q attached, substantially as and for the purpose set forth.

GEO. W. VAN BRUNT.
